UNITED STATES PATENT OFFICE.

EARL J. WHITTAKER, OF ABERDEEN, WASHINGTON, ASSIGNOR TO HARVEY W. BAILEY,
OF SEATTLE, WASHINGTON.

CUTTING MACHINE FOR THE MAKING OF SHINGLES.

Application filed June 16, 1927. Serial No. 199,209.

- This invention relates to shingle machines, and provides as its basic object a mechanism for cutting wood, fiber or other shingles, and which machine is of few parts, simple 5 in construction, assembly, adjustment and operation; economic and of high efficiency in action, low in manufacturing costs, and which may be readily transported to or installed in any desired place.
- Another object of my invention is to provide in a machine of this nature, means for preventing the making of and for using the waste portions of wood substance which are at present made by saws or cutting 10 machines, which waste in such instances takes the form of sawdust and "spalt". My machine provides for the making of dustless cuts, and for using all of the "spalt" that is available for the manufacture of 15 shingles.
- A further object of my invention is to provide in such a machine a plurality of knives, feed-rolls and operating controls for blocks, so that several "cuts" may be made 20 each time the knives complete a single gyration.
- A further object of my invention is to provide a differential motion to the knives, so that they may enter the blocks at relatively higher "advance," or shearing speed, and leave the "cut" at a low "advance", or 25 slicing speed, to prevent, in all events, the "cut" from "splitting" from the block.
- A further object of my invention is to 30 provide in such machine, means to operate and control at will the positive, even and differential feeding of the blocks into the cutting areas of the knives, and to firmly hold such blocks in proper position to establish and deliver the desired "cuts".
- A further object of my invention is to 35 provide means whereby blocks of irregular shape may be radially advanced into the cutting areas of the knives by the positively controlled motion of the feed-rolls contacting the ends of the blocks, thus feeding one or either end of such blocks only, and when cutting shingles, to make "butt-cuts" only 40 from such "feed end", repeating this process until the blocks are cut to regular shape; thereafter to alternate the "feed" of the blocks so that first a "tip" and then a "butt" of a shingle will be cut from the blocks fed 45 to the knives in the manner prescribed.
- A further object of my invention is to 50
- provide means for feeding and control of a plurality of blocks into the knife areas of any one or more of the several feed-rolls, whereby such blocks may be fed and positively controlled for cutting "standard" and "dimension" shingles, or otherwise. 55
- A further object of my invention is to provide in connection with the feed-rolls of such mechanism, means for holding the "spalt" of each block, and to cut same into shingles, while said "spalt" is being crowded down into the knives by the block next descending into their cutting areas. 60
- A further object of my invention is to provide in such mechanism means for establishing, operating, controlling and for balancing the "throw" of the knives in such manner that their "advance" into the cutting areas and their retreat therefrom shall be in constant equipoise, and that their operation shall produce no vibration within or undue strains upon such machine, that may in any manner affect its perfect control and work. 65
- A further object of my invention is to provide, in connection with such mechanism, for controlling, establishing, operating and synchronizing each moving part of same, so that the timing and performance of the "cuts" made may equalize any vibration of parts and may counteract the strains induced 70 by a change of feed, throw of feed, frequency 75 of gyration, or otherwise.
- Other objects will appear by a reference to the specifications describing my invention and to the drawings illustrating the same, in which— 80
- Fig. 1 is a plan view of my improved cutting machine, illustrating the cam and bell-crank arrangements for operating certain feed-rolls. 85
- Fig. 2 is a vertical sectional view taken substantially on the line 2—2 of Fig. 1. 90
- Fig. 3 is a sectional view taken on the line 3—3 of Fig. 1. 95
- Fig. 4 is a cross-section on the line 4—4 of Fig. 1, illustrating the block-feeding rolls and the spalt bar arrangement. 100
- Fig. 5 is a vertical section of one of the roller-ratchet-grips for operating the feed rolls. 105
- Fig. 6 is an elevation of a detached block feeding roll adjustment and its connecting mechanism. 110
- Fig. 7 is a central vertical section of the

cam arrangement for operating certain bell-crank.

Fig. 8 is a plan view of one of the saddle-driving discs.

5 Fig. 9 is an enlarged section of the spalt-bar and showing its association with certain feed rolls.

Describing the mechanism and drawings in detail the reference numeral 1, designates 10 the machine frame which suitably supports all its fixed and working parts.

Numeral 2, designates bearings which seat and carry shaft 2^a, pinion 5 and friction disc 4 which is driven by power-driven 15 pinion 3. Suitably fixed to the base and top of machine frame 1, are bearings 7 and 8, seating and carrying the central main drive-shaft 9, to which is keyed gears 6, 10 and 11, and collars 12. Selectively affixed to the 20 machine frame 1, bearings 13 and 14 carry the driven shafts 15 (see Fig. 1), to which shafts are keyed gears 16, meshed with and driven by gear 10 thru driving-shaft 9. To the upper part of shafts 15 are keyed driving 25 discs 17, seating and driving the saddle 18 carrying the knives 21, the controlled action of which is to cut or slice regular or irregular shaped pieces from wooden blocks, or other similar materials fed into their cutting 30 areas by block feed-rolls 26, thru openings 24. (See Figures 1 and 3.)

The saddle 18, preferably in the form of an annulus, is seated upon and driven by crank-pins 19 which are adjustably seated in 35 slots 20 grooved within discs 17. At one or more positions on the periphery of saddle 18, the knives 21 are selectively attached, preferably seated thereon with their plane edges facing upward beneath bed-plate 22, and 40 their bevel edges facing downward. By the action of driving discs 17, saddle 18 is arranged to rotate through suitably adjustable arcs in a horizontal plane, registering a cutting action to the knives that is greatest in length 45 of stroke at the beginning of their "cut", and greatest in their "drag" or slicing movement at the end of such stroke, thereby tending to prevent the splitting of the "cut" from the face of the block under treatment.

50 In Figure 1 the numeral 21^a shows the position of one of the knives beneath the opening 24 at the end of its stroke, each of said knives being carried on the saddle-lug 18^a, which lug is cast integral with the saddle 18. Thus, numeral 21, showing the knives affixed to the saddle 18, and the positions assumed in cutting off a shingle from 55 a block, as such blocks are fed into the cutting areas of the knives by feed-rolls 26.

60 The knife at the top is withdrawn from under the block, and when the machine is operated as a plural block-cutter, the feed rolls on that side will, with the cam and bell-crank arrangement, about to be de- 65 scribed, set or feed the block downward a

distance equal to the thickness of a shingle; and likewise, such order will proceed, alternately in the feeding of said blocks into the cutting areas of the knives, around the machine.

70 Drive shaft 9 projects upward thru the bed-plate 22, such shaft mounting and driving pinion 11 in mesh with gear 33. (See Figure 2.) Openings 24 are located in suitable positions in bed-plate 22, over which 75 openings or freeways and slidably affixed in suitable grooves in said bed-plate, is seated the feed-roll frames 25 on which is mounted bearings 27 supporting shafts 29 carrying feed-rolls 26. Said feed-rolls 26 are adapted 80 to automatically feed regular or irregularly shaped blocks into the cutting areas of the knives 21, and may be controllably regulated to register any desired standard or dimension "cut".

85 Referring to Figures 3 and 4, each respective set of feed-rolls 26, carry their "spalt-bars" 28 rotatably mounted on shafts 29 by rings 51, which "spalt-bars" by means of their sharp, toothed edges 28^a are arranged 90 to grasp and firmly hold the "spalt" as such toothed edges are pressed into the ends thereof by the reaction of the selectively adapted springs 48 that are seated against the rearward portion 49 of said "spalt-bars" 28 and 95 bracket 50, a fixture attached to the feed-roll frames 25 to fulfill the purpose expressed. By this action of the "spalt-bars" 28, and while being crowded down thru the feed rolls 26 by other blocks coming into position 100 for cutting, shingles may be cut from said "spalt" until the same is completely utilized.

In the rearward portion of said "spalt-bars" 28, studbolts 52 may be fitted in hole 52^b (see Fig. 4) the free ends of which studbolts are fixed within suitable openings 52^a in bracket 50, and positioned with jam-nuts 53 so that sufficient play will be allowed for "spalt-bars" 28 to be operated by springs 48, and said bars will properly engage the 110 "spalt" while the shingles are being cut therefrom, and will release the "spalt" when same is being adjusted or positioned for a new "cut". "Spalt-bar" 28 is of triangular-shape, its wings 28^c being of suitable size 115 for mounting between the sections of feed-rolls 26. Feed-roll 26 is made in three sections with key-way in its bore as shown. In the assembly of the feed-rolls, the rolls are mounted to shaft 29 said rolls being separated by rings 51 a distance sufficient to allow for the free movement of the "spalt-bars".

Rings 51 are of smaller diameter than the central cross-sectional measurement of the feed-rolls, and said rings are of equal size 120 as hole 28^b in "spalt-bars" 28. Feed-rolls 26 are machined to right length to fit longitudinally inside of "spalt-bar" wings 28^c, which, when placed on the shaft 29, rings 51 forms a bearing for and fits inside of 125 130

hole 28^b (see Fig. 9), in "spalt-bar" 28. Said feed-rolls, with their spalt-bars, being assembled in three sections on shaft 29, allows said rolls to revolvably feed and hold more than one block of slightly different lengths at the same time, and to feed same differentially into the cutting areas of the knives 21 during the operations herein described.

In Figure 6, the feed-roll adjustment device 30, controlled by hand-wheel 31, (see Fig. 1), may be set to alternately, or directly, cut "butts" and "tips" ends, such control mechanism 30 being driven by cam and bellcrank arrangement as shown in Figure 1. Drive pinion 11 (see Figures 1 and 2) operates gear 33 carried on shaft 34 and is seated in bearings 35, said shaft and bearings being suitably supported by frame 36 bolted to bed-plate 22, as shown in Figure 2. The upper part of shaft 34 carries a cup or inverted cylinder 37 in which slots 39, (see Fig. 7), serve as seatings wherein to adjustably fix cams 40, by means of stud-bolts 41 passing through said slots 39 and being tightly secured or held by locknuts 38 affixed to stud-bolts 41. In operation, as gear 33 rotates cylinder 37 by means of shaft 34, cams 40 oscillate the bellcranks 54 on axes 55, and by adjustments 56 and levers 57, give selective and adjustable movement to mechanism 30, controlling the operation of feed-rolls 26 with their "spalt-bars" 28, substantially as described, and as specified in the objects thereof.

An elevation represented in Figure 6, shows in detail the mechanism of the feed-roll controls or adjusting devices 30 by which the positive control of feeding the shingle blocks into the cutting areas of the knives 21, is regulated, each of said devices being driven by power-arm 58 thru axis 59 on disc 60. Said disc 60 is of suitable size to carry and space the control arms 61, 62, 63 and 64 which drive and control the operation of each of the roller-grips 65, shown in sectional detail in Figure 5. Returning to Figure 6, disc 60 is mounted on axis 66 which is suitably provided and adjustably fixed to bed-plate 22. Disc 60 is provided with a vertical slot 67 in which, crank pins 68, 69, 70 and 71 are adjustably fixed, and which crank-pins act as axes of the control rods 61, 62, 63 and 64, for operation and control of roller-grips 65. In Fig. 1 cams 40 on cylinders 37, shown in plan selectively, oscillate bellcranks 54, power being supplied thru gear 33 and shaft 34 as illustrated and described aforesaid. Bellcranks oscillating on axis 55 convey their movement thru connecting rods 57 and 58, and hence to disc 60 and to roller-grips 65.

Upon inspection of Fig. 1 it will be observed that I provide two of these roller-grips for each feed-roll shaft 29: each pair of said grips (65) are assembled in reverse

relation to each other. In Fig. 5 is shown the feed-roll shaft 29 on which disc 72 is keyed. Over said disc 72, sleeve ring 73 is slipped, which ring 73 carries a wing projection 73^a on one side, to which wing an operating lever, such as 62, may be attached at hole 73^b. On the inside of ring 73 is a plural number of slots 74 extending into the inner face of ring 73, and in which are placed rollers 75 of desired size. Between said rollers 75 and the back of said slots 74 are springs 76 of ample strength to hold rollers 75 against the circumferential surface of disc 72. Pulling downward on wing 73^a of ring 73 rollers 75 become wedges between the circumference of disc 72 and the upper sides of slots 74, forming a non-slipping contact between said disc and ring (this action causes the block feed-roll 26 to turn in its bearings 27 delivering a selective and positive feed to its block). In connection with this mechanism I have provided an attachment to control and release the roller-grips 65, whereby the operator may hold said rollers 75 away from the periphery or face of the disc 72, causing the ring 73 to move around the circumference of disc 72 in either direction without turning feed-roll 26. This action is explained by the operation of pins 77 which are inserted in holes 77^a drilled into the circumferential face of ring 73 at right positions so that when said pins are placed in the holes as stated, their bevelled points 78 will contact and press against the side of rollers 75, and being pressed inward by band-ring 79, said rollers 75 will move back against springs 76 and into the slots 74, and will be held in that position as long as pressure is applied to band 79, as described. To accomplish such action I have provided steel band ring 79 fitted in concentric relation to the outer circumference of ring 73, and over the head of pins 77, connecting the free ends of said band 79 to two bent levers 80, and with axis 81 common to each. Between the outer ends of said levers, cams 82 are placed, and by turning said cams by means of handwheel 31 thru a prescribed arc (in this instance approximating 90 degrees) the outer ends of angle-levers 80 may be separated in alternate relation which movement draws the inner ends of said levers together, thus tightening band 79 and pressing radially inward upon pins 77 driving them into their respective sockets against their springs 84 (which springs are held by said pins 77 between their large disc-like heads, and the rim of ring 73), thus releasing the grips between ring 73 and disc 72, and allowing said ring free movement in either direction. Cam 82 is operated by connecting rod to the operator, the parts being shown in Figures 1 and 5. The two roller-grip block setters connected to the end of each block

feed-roll are placed in a reverse position, as shown in Figs. 1 and 6. This assembly is made necessary in order to cut alternate "butts" and "tips" of shingles; the reason 5 for this formation of mechanism is explained in description of Figure 6.

Between shafts 29, to each of which is connected the two roller-grip arrangement or mechanism 65, is placed disc 60, which 10 vice regulates and controls the action of roller grips 65 by means of rods 61, 62, 63 and 64 attached to adjustably positioned pins 68, 69, 70 and 71 which are placed or fixed in slot 67 grooved across the face of disc 60. 15 Disc 60, mounted on shaft 66, as illustrated, may oscillate with a given throw provided thru rod 58. When rod 58 is moved to the right, disc 60 pulls on rods 61 and 64, both of which are adjustably connected near 20 the outer rim of disc 60, and which, therefore, have a longer throw than rods 62 and 63 which are adjustably connected near the center of said disc and consequently have a shorter throw upon said rods. In such in- 25 stance rods 61 and 64 operating thru roller-grips 65 moves block feed-rolls 26 thru a greater arc than can rods 62 and 63. This action causes the blocks being fed into the cutting areas of the knives 21 to move 30 downward a distance pre-determined as to each end of such blocks being so fed, thus providing for the cutting of the "butts" of shingles by the motion of rods 61 and 64 regulating the long throw; and for the 35 "tips" of shingles by movements of rods 62 and 63 regulating the short throw in said device. By a reversal of this action an opposite result is obtained, thus providing for the alternate and successive making of a 40 "butt" and "tip" of a shingle at each end of such blocks.

In the illustrations shown in Figure 1, is 45 shown a plan of a pair of roller-grips 65, for controlling and setting the feed-rolls 26. Said grips may be connected to feed- roll shafts 29 in opposition to each other, which position allow said devices to grip in alternate succession as they oscillate around the circumference of discs 72 with or 50 upon shafts 29. The action of such control is accomplished by the automatic release of the rollers 75 as the rods 61 and 62, being connected to opposite roller-grip rings at one end and being seated at the 55 other in crank-pins 70 and 71. Reverse grip may thus be moved about the circumference of disc 72 without interfering with a contrary movement of its opposite disc.

A sectional view of the barrel-shaped 60 cam-holder or cylinder 37, shown in Figure 7 and plan shown in Figure 1, the cams 40 are placed in alternate relation on the outside circumference of said cylinder walls in such position that when cam 40 has moved 65 forked bellcrank 54 to one side, the adjust-

able weight-arm of said bellcrank has transferred said motion thru rods 57 and 58 to the feed-roll control mechanism 30, setting said feed rolls 26 for a desired "cut". The reverse movement of said bellcrank reverses 70 the action of the roller-grip, thus providing for the regulation and successive control of such "feed" and "cuts" from the blocks passing thru feed-rolls 26. Numeral 40 designates the cam showing stud-bolt 41, said 75 stud-bolt when assembled to be inserted in slots 39 in cam-holder or cylinder 37, cam 40 being adjustable about the circumference of cylinder 37, whereby the timing of feed-rolls 26 may be pre-adjusted and regulated 80 as a determined control for "cuts" to be made from feed blocks.

Again referring to Figure 8 which shows a plan of one of the discs 17, also showing adjustable balance weights 45 for regulating the impulse and throw of knives 21. Disc 17 is cut away, as indicated at 42, to admit the weights 45 and to provide for their adjustment thru a greater or lesser segment of arc within the body of disc 17. Weights 90 45 are provided with wings 46 in which hole 46^a is drilled as a bearing to fix and suspend said weights upon shaft 15 within disc 17. Said weights are of suitable size and shape to provide the utmost in balancing effect. 95 Stud-bolts 44 are fitted thru slots 47 cut thru the web 43 of disc 17. A lock-nut 44^a on each stud-bolt will hold weights 45 firmly in position for operation. The function of said weights is to adjustably and accurately 100 balance the reaction, or throw, of the saddle-frame 18 with its knives 21, as said saddle-frame and the knives gyrate about their given orbit.

Having described my invention, what I 105 claim is:

1. In a shingle cutting machine, a bed plate having a block-receiving opening therein, a cutter operable beneath said opening, a rotatable element connected to said cutter and adapted to move the same at variable speeds below and across said opening, means for adjusting the speed of said cutter, and means for operating said element.

2. In a shingle cutting machine, a bed 115 plate having a block-receiving opening therein, a cutter operable beneath said opening, a rotatable element connected to said cutter and adapted to move the same at variable speeds below and across said opening, counterbalance means adjustably associated 120 with said rotatable element for regulating the speed of said cutter and means for operating said element.

3. In a shingle cutting machine, a bed 125 plate having an opening therein, means for feeding a block to a cutter, said means embodying spaced rolls rotatively mounted in said openings and adapted to feed the block therethrough, spalt-bars carried by the axes 130

of said rolls and operable therewith, and tension means for holding said bars against a block.

4. In a shingle cutting machine, a bed plate having an opening therein, means for feeding a block to a cutter, said means embodying spaced rolls rotatively mounted in said openings and adapted to feed the block therethrough, spalt-bars carried by the axes

10 of said rolls, means for limiting the movement of said bars and tension means for holding said bars against a block.

5. In a shingle cutting machine, a bed plate having an opening therein, means for feeding a block to a cutter, said means embodying spaced rolls rotatively mounted in said openings and adapted to feed the block therethrough, spalt-bars carried by the axes of said rolls, adjustable means for limiting 20 the movement of said bars and tension means for holding said bars against a block.

6. In a shingle cutting machine, block feeding rolls, means for operating the block-

feeding rolls, said means comprising a rotatable cylinder, a plurality of cams adjustably carried thereby, an oscillatory bell-crank adapted to be engaged by selected cams, roller-grips associated with said rolls and adapted to be operated by said bell-crank and manual means for controlling 30 and releasing said roller-grips to regulate the action of said feed-rolls.

7. In a shingle cutting machine, a cammed cylinder adapted to be rotated, a pivoted bell-crank operated by said cylinder, an oscillatory disc connected to said bell-crank, a plurality of spaced block-feeding rolls, roller-grips associated with said rolls, levers connecting said oscillatory disc and said roller-grips and adapted to be operated to 40 vary the rotation of said rolls and manually operable means for uncoupling said roller-grips from their connected rolls.

In testimony whereof I affix my signature.

EARL J. WHITTAKER.
